(57) **CLAIM**

The ornamental design for a frame for a bicycle, as shown and described.

DESCRIPTION

FIG. 1 is a front, left and top perspective view of a frame for a bicycle, showing our new design;

FIG. 2 is a rear, right and top perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top plan view thereof; and,

FIG. 8 is a bottom plan view thereof.

The broken lines in the figures illustrate portions of the frame for a bicycle that form no part of the claimed design.
